COMBINED MICROPHONE STAND AND AMPLIFIER

George Sharpnack, Lincoln, Nebr.

Application December 5, 1935, Serial No. 52,974

7 Claims. (Cl. 179—147)

This invention relates to microphones and supports therefor, and has for an important object thereof the provision of a support which will permit greater ease in the use of the microphone.

Another object of this invention is to provide a combined amplifier cabinet and microphone stand which will permit the person speaking into the microphone or otherwise broadcasting to directly control the output.

A further object of this invention is the provision of a compact unit including an amplifier and microphone which is so constructed and arranged as to give a greater distance between the input of the amplifier and the output and power unit, thus greatly reducing the inductive field which normally emanates from the output end of the amplifier and which causes an undesirable amount of hum to be picked up at the input side of the amplifier. The combining of the amplifier unit and the microphone and stand therefor will permit greater ease in handling, controlling and setting up the equipment by reason of the fact that two otherwise cumbersome units are combined into one unit, and the controlling is done by the person standing before the microphone.

The microphone switch 29 is particularly new and useful because it not only turns the microphone off and on, but does it by disconnecting the plate circuit to the entire amplifier, thereby removing all voltage strain from the entire amplifier when it is not in actual use.

With the foregoing and other objects in view, the invention will be more fully described hereinafter, and will be more particularly pointed out in the claims appended hereto.

In the drawing, wherein like symbols refer to like or corresponding parts throughout the several views:

Figure 1 is a detail front elevation of a microphone and support therefor constructed according to an embodiment of this invention.

Figure 2 is a vertical section taken substantially through the center of the stand and showing the arrangement of the parts comprising the amplifying unit.

Figure 3 is a top plan of the support with the microphone removed therefrom.

Figure 4 is an enlarged sectional view taken on the line 4—4 of Figure 2.

Referring to the drawing wherein like symbols designate corresponding parts throughout the several views, the numeral 10 designates generally a support or cabinet which comprises a base 11 of hollow construction and a standard 12 which at its lower end is secured to the base 11

as by threads 13 or the like. The interior of the base 11 forms a chamber 14 in which one or more portions of an amplifying unit may be placed in this chamber. The side wall of the base 11 may also have one or more sockets 15 which are in connection with the amplifying unit so that the stand and the parts enclosed thereby may be connected by means of extension wires to the loud speakers.

The standard or housing 12 is constructed substantially cylindrical in form, although the configuration of this housing 12 may be varied to suit the needs or desires of the manufacturer and user. The housing 12 is provided with a plurality of windows 16 through which the tubes contained in the cabinet may be viewed and so that these tubes may be suitably ventilated or cooled.

The parts comprising the amplifying unit and the circuit or circuits therefor are conventional, and are here shown as an illustration of the manner in which such parts may be arranged, the connections between the several parts being eliminated, as neither the parts nor the circuit or circuits in which the parts are interposed form a part of this invention.

A plurality of shelves or partitions 17 are disposed within the housing 12 in vertically spaced apart relation, and each shelf or partition 17 is adapted to support one or more of the parts comprising the amplifying unit. The shelves or partitions 17 are held in spaced apart relation by means of sleeves 18 which loosely engage about rods 19 extending throughout the length of the cabinet or housing 12. These rods 19 extend through a top panel 20, having a head 21 above the top 20, and also extend through a bottom plate 22. Suitable nuts or other securing means may engage the lower ends of the rods 19 so as to hold the shelves or partitions together as a unit. The entire assembly of shelves or partitions may be removably secured within the cabinet or housing 12 by providing a shoulder 23 at the top of the cabinet or housing 12 and extending bolts 24 through the housing into recesses provided in the peripheral portion of the top panel 20.

The top 20 of the cabinet constitutes the instrument panel, and may have a pair of controls and knobs 25 and 26 mounted thereon. A lamp 27 is mounted on the panel 20 in a suitable socket provided therefor, and this lamp may be of a suitable identifying color, such as red, so as to serve as a signal to the person or persons about to start broadcasting that the amplifier is turned "on". A second lamp 28 may also be mounted on the panel 20, and this lamp 28 may be of a con-

trasting color with respect to the lamp 27, such as green, and when this lamp 28 is lighted it serves as a signal to the person or persons about to broadcast that the microphone is connected.

5 A plate voltage controlling switch 29 is mounted on the panel so that when the person using the equipment is ready, he may easily put the amplifier and microphone into use by moving the switch 29 to closed position, and thus place the 10 microphone in circuit with the loud speakers to which the amplifying unit is connected. The filaments to the tubes mounted in the cabinet 10 are turned on by means of a snap switch 30 which in the present instance is mounted on the 15 projecting portion of the base 11. By placing the "heater" switch 30 on the base 11, the tubes incorporated in the amplifying unit may be maintained in a heated condition so that the device is ready for instant use, and in the event the operator becomes confused the current will not be turned off accidentally, and it will not be necessary to wait for the tubes to become heated before the unit is operative.

A socket 31 is carried by the panel 20 in which 25 one end of a flexible tube 32 is adapted to be threaded or otherwise secured, and this tube 32 is preferably of the type which may be bent and which will retain its bent form. The tube 32 has a microphone 33 secured to the upper end thereof, and the wires for the microphone are adapted 30 to extend down through the tube 32. Any suitable form of terminals or contacts may be used to detachably connect the wires leading to the microphone with the input side of the amplifying 35 unit contained in the cabinet 10.

During the assembly of this combined microphone and amplifying unit, the parts may be mounted on the shelves 17 which are held in spaced apart relation by means of the sleeves 18, 40 and the entire shelf unit is held in assembled condition by means of the rods 19. With the shelf unit removed from the cabinet 10 the various parts of the amplifying unit may be conveniently connected together, and the tube shelves are preferably so arranged that the tubes 45 on such shelves will be exposed through the windows 16 of the housing 12. After the parts of the amplifying unit are properly connected in the proper circuits the entire assembly may be slipped into the housing 12, with the top panel 50 resting on the shoulder 23. The screws 24 may then be tightened or other suitable means provided to tightly hold the shelf unit within the cabinet. The base 11 may have a removable 55 panel in a wall thereof to permit proper connection of the output end of the amplifying unit with the socket 15 or with any part of the amplifying unit which may be disposed in the base chamber 14.

60 Assuming that a person is to speak into the microphone, the heater switch 30 is initially turned on a sufficient time before using so as to permit the heater portions of the tubes to attain the proper temperature. Just prior to the time 65 that the outfit is to be used the operator will close the snap switch in the base which will light the red lamp 27 and turn the filaments of the tubes "on". At the moment a person desires to speak or play into the microphone, the plate controlling switch 29 is closed, and at that instant 70 the microphone is in circuit and the broadcasting may begin.

By reason of the compactness of this cabinet 75 and support, and by reason of the arrangement of the parts comprising the amplifying unit,

there will be a minimum of stray inductive fields causing hum or distortion, and the entire device may be stored in a relatively small space with the goose-neck support for the microphone secured to a suitable case which may be secured to the side of the housing 12.

It is obvious that various changes and modifications may be made in the details of construction and design of the above specifically described embodiment of this invention without departing 10 from the spirit thereof, such changes and modifications being restricted only by the scope of the following claims:

What is claimed is:

1. A cabinet and microphone support comprising 15 a base, a hollow standard extending upwardly of the base, a shelf unit within the standard and including a plurality of spaced apart shelves secured together, a top panel carried by the shelf unit, a microphone, and adjustable means connecting the microphone with the panel.

2. A cabinet and microphone support comprising 20 a base, a hollow standard extending upwardly of the base, a plurality of vertically spaced apart shelves disposed in the standard, means for securing the shelves together, means for removably suspending the shelves as a unit within the standard, a microphone, and means for securing the microphone to the upper portion of the shelves.

3. A cabinet and microphone support comprising 25 a hollow base, a hollow standard, means for detachably securing the standard to the base, a plurality of spaced apart shelves, means for securing the shelves together as a unit, means for suspending the shelf unit within the standard, a microphone, and flexible means for securing the microphone to the shelf unit.

4. A cabinet and microphone support comprising 30 a hollow base, an elongated hollow standard, means for detachably securing the standard to the base, said standard having a plurality of windows through a wall thereof, a plurality of spaced apart shelves, means for securing the shelves together as a unit, certain of said shelves being disposed adjacent said windows, means for removably securing the shelf unit within the standard, a microphone, and means for securing the microphone to the shelf unit.

5. A cabinet and microphone support comprising 35 a hollow base, an elongated hollow standard, means for detachably securing the standard to the base, said standard having a plurality of windows through a wall thereof, a plurality of spaced apart shelves, means for securing the shelves together as a unit, certain of said shelves being disposed adjacent said windows, an instrument panel carried by the upper portion of said shelf unit, a microphone, and adjustable connecting means connecting the microphone with the instrument panel.

6. A cabinet and microphone support comprising 40 a hollow base, a hollow cylindrical standard secured to and extending upwardly of the base, said standard having a plurality of windows through a wall thereof, a plurality of spaced apart shelves, means for securing the shelves together as a unit, certain of said shelves being disposed adjacent said windows, an instrument panel carried by the upper portion of said shelf unit, a microphone, and flexible connecting means connecting the microphone with the instrument panel.

7. A cabinet and microphone support comprising 45 a base, a hollow cylindrical standard secured

to and extending upwardly of the base, a plurality of spaced apart annular shelves, a plurality of aligned spacer sleeves disposed between the shelves, a plurality of tie rods extending through aligned sleeves for securing the shelves together in spaced apart relation as a unit, an instrument

panel carried by the upper portion of said shelf unit, means for removably securing the shelf unit within the standard, a microphone, and means for detachably securing the microphone to the shelf unit.

GEORGE SHARPNACK.
